UNITED STATES PATENT OFFICE.

CHESTER A. KELLOGG, OF BARTONVILLE, ILLINOIS, ASSIGNOR, BY MESNE ASSIGNMENTS, TO THE UNION TRUST COMPANY, OF CLEVELAND, OHIO, A CORPORATION OF OHIO, AND JOHN A. CHAPMAN, TRUSTEES, OF CHICAGO, ILLINOIS.

METHOD AND APPARATUS FOR FIRING FURNACES.

1,402,773.

Specification of Letters Patent. Patented Jan. 10, 1922.

Application filed February 9, 1920. Serial No. 357,203.

To all whom it may concern:

Be it known that I, CHESTER A. KELLOGG, a citizen of the United States, residing at Bartonville, in the county of Peoria and 5 State of Illinois, have invented new and useful Improvements in Methods and Apparatus for Firing Furnaces, of which the following is a specification.

This invention has reference to a method 10 of converting gas fired regenerative furnaces to furnaces in which fuels which do not require preheating in regenerative chambers may be burned, such as petroleum or other oils; powdered coal; tar; natural, artificial, 15 illuminating or coke oven gas, or combinations of the above, and to an apparatus for permitting the burning of such fuels in such furnaces when converted from gas.

For the sake of clearness and brevity I 20 am confining myself in the following description to the use of liquid fuels, and still further for the sake of brevity, to oil. That the invention may be more fully understood, reference is had to the accompanying drawings 25 forming a part of this description, showing a well known type of gas fired regenerative furnace with the preferred embodiment of my invention applied thereto.

Fig. 1 is a diagrammatic view showing 30 the opposite ends of a gas fired regenerative furnace with the air and gas systems, and stack, or waste heat boiler connected thereto, the arrangement, showing the furnace to be fired with gas;

Fig. 2 is a diagrammatic view somewhat 35 similar to Fig. 1, but showing the preferred furnace arrangement when fired with oil and with my invention applied to permit conversion from gas fired to oil fired;

Fig. 3 is a vertical longitudinal sectional 40 view through the left hand end of the furnace looking at Fig. 1, to show the arrangement of the gas and air slag pockets, the uptakes and the gas and air ports connecting the uptakes with the furnace proper;

Fig. 4 is a vertical cross-section of the 45 furnace looking toward one end, and is approximately the same as would appear if taken along the line 4-4 of Fig. 5 in the direction of the arrow, and

Fig. 5 is a cross-section in plan through the gas and air slag pockets, and is as the

same would appear if taken on the line 5-5 Fig. 4 in the direction of the arrow.

Like characters of reference denote corresponding parts throughout the figures.

Those skilled in the art to which this invention pertains will readily understand the construction of the furnace shown, and its intended operation when gas fired, and those 60 who have had experience with oil firing will understand the attempts which have been made to convert such a furnace, as shown, from gas fired to oil fired, without the necessity of specific reference to the various elements of the furnace and their uses; but that a very clear and concise understanding may be had of my method of conversion from a gas fired to an oil fired furnace, and the use of the 65 apparatus, I shall very briefly point out the 70 various elements of the furnace and the direction of the gas and air, as well as the oil when using the furnace.

Such a furnace as I have shown includes 75 the opposite end gas checker chambers 1 and 1^a, communicating with gas slag pockets 2 and 2^a respectively, which in turn communicate with gas uptakes 3 and 3^a respectively; the air checker chambers 4 and 4^a which communicate with the air slag pockets 5 and 5^a respectively, which in turn communicate 80 with the air uptakes 6 and 7, and 6^a and 7^a respectively. 8 and 8^a designate the gas systems which are connected with the gas checker chambers 1 and 1^a respectively; and 85 9 and 9^a designate the air systems which are connected with the air checker chambers 4 and 4^a respectively. The gas and air systems include the reversing valves 10, 10^a and 11 which are employed, as understood 90 in the art, to permit the alternate reversal of direction of the gas and air to the respective gas and air checker chambers 1 and 4, and 1^a and 4^a.

By the arrangement of the system as illustrated in Fig. 1 (the furnace being fired with gas) the gas enters the gas checker chamber 1, passes through the slag pockets 2, and up through the uptakes 3 into the body of the furnace mingling with air as it 100 enters the body of the furnace, which said air enters through the air checker chamber 4, thence into the slag pocket 5 and up through the air uptakes 6 and 7. The prod-

ucts of combustion pass through the furnace proper, and the waste gases exhaust down through the air uptakes 6^a and 7^a and the gas uptakes 3^a, through the gas and air checker chambers 1^a and 4^a and out through the stack or the waste heat boiler 13. This operation continues for about fifteen minutes, when the reversing valves 10, 10^a and 11 are shifted into the dotted position shown in Fig. 1, when the direction of intake of gas and air and the exhaust of the waste gases is changed—i. e. the gas then enters the furnace through the checker chamber 1^a, the slag pocket 2^a and through the gas uptake 3^a, such gas mixing with the air which enters the furnace through the air checker chamber 4^a, slag pocket 5^a and up through the air uptakes 6^a and 7^a. The products of combustion, or waste gases leaving the furnace through the gas and air uptakes 3, 6 and 7 respectively, and through the gas and air slag pockets 2 and 5 respectively, the gas and air checker chambers 1 and 4 respectively and out through the stack 12 or waste heat boiler 13. This operation continues for approximately fifteen minutes, when the cycle is again reversed, and so on until the heat is ready to tap.

In Fig. 2, which is a diagrammatic illustration showing the furnace converted to oil burning, I have shown the gas uptakes 3 and 3^a blocked off and also shown the gas and air slag pockets 2 and 5, and 2^a and 5^a connected by flues 14 and 14^a communicating with said slag pockets through the slag pocket bulk-heads. With this arrangement air may be introduced through either of the systems 8 and 9 or 8^a and 9^a, which entering through the checker chambers will pass into the slag pockets and into the body of the furnace through the uptakes 6 and 7 or 6^a and 7^a; the air which passes into the slag pockets 2 and 2^a, not finding egress through the uptakes 3 and 3^a will pass into and through the flues 14 and 14^a commingling with the air entering through checker chambers 4 and 4^a and passing into the body of the furnace through either of the uptakes 6 and 7 or 6^a and 7^a to assist in the proper combustion of the oil which is forced into the furnace under pressure, in a manner and for purposes more fully to be explained.

Referring to Fig. 3, I have shown a refractory wall 15 which blocks off the opening providing communication between the gas uptake 3^a and a gas port 16, and have removed the end bulkhead at the point 17 of the gas port 16 to provide for the insertion or placing of the oil burner 18 suitably connected with a source of oil supply. In the forward end of the gas port 16, I have shown a refractory partition 19 provided with an opening 20 through which the nozzle of the oil burner 18 protrudes for the discharge of the oil into the body 21 of the

furnace where it meets the air entering the body of the furnace through the air port 22 which communicates with air uptakes 6 and 7, or 6^a and 7^a, depending of course on which end of the furnace you are looking at. 70

In Figs. 4 and 5 the flue 14 or 14^a is shown more in detail and comprises the necks 23 which communicate with the adjoining gas and air slag pockets upon opposite sides of the partition wall 24 which separate said slag pockets, and also with the main body portion of such flue or flues, as will be understood. The last foregoing description shows the manner and form (Fig. 3) in which the upper ends of the gas uptakes 3 and 3^a are 80 blocked off, together with the removal of the wall at 17 to permit the introduction of the oil burner, or burners in the ports ordinarily used for the introduction of gas into the furnace proper. With such changes, as I have 85 previously explained, air will be introduced through the slag pockets 2 and 5, or 2^a and 5^a which passes into the furnace through the port 22; the oil forced into the burner 18 meeting the air at the point of combustion 90 where the air and oil enters the body 21, of the furnace, (see Fig. 3). Should it be desirable or expedient to re-convert the furnace from oil burning to gas burning, all 95 that is necessary to do is to remove the refractory wall 15, the partition 19, withdraw the oil burner 18, again block up the end of the port 16 at the point 17 and block up the bulk-heads of the gas and air slag pockets at the point where the necks 23 of the 100 flues 14 or 14^a communicate with said slag pockets.

I aim with my method of conversion from gas to oil burning and apparatus for this purpose to make the change from gas 105 to oil burning without interfering with the operation of the furnace unless it be for the very shortest possible space of time and without the necessity of cooling down or stopping the furnace entirely. I do not claim to being the first to convert a gas fired regenerative furnace to an oil burning furnace, except by a method and means which will prevent the complete shutting down of the furnace and at a great loss of time and money. In other words, by my method and means, I do the work so expeditiously as not only to save in the operation, which is very material from a financial viewpoint, but during such change am able to operate 120 continuously, and to this extent increase the production materially. It is a proven fact, which I have found by experience, that by the use of oil, production in tons of steel is materially increased, when working with 125 cold charges, and by the method which I employ for the conversion of the furnace from gas fired to oil fired, I am able to maintain the production during the period of time when such change is made effective. 130

The reason for increased production under the conditions which I have stated is by reason of the fact that flues 14 and 14^a permit of enough ingress and egress of air and waste gases so that an ample amount of fuel may be burned at all times.

I will now describe the steps employed when changing the furnace from gas fired to oil fired without the necessity of shutting down or cooling the furnace. We will assume that the system of operation is that shown in the diagrammatic view Fig. 1. Both flues 14 and 14^a and connected necks 23 are constructed to the point of breaking down parts of the slag pocket bulk-heads to connect the flues by means of the necks 23 with said slag pockets. During the interval of time when the furnace is fired with gas passing into the checker chamber 1, the wall at 17 of the opposite gas port from that in which the gas is entering the furnace, is removed and a suitable shield, not shown, is inserted into the gas port to block the inner end compelling the products of combustion to pass out through the air port 22. When this blocking off of the gas port has been accomplished then the upper end of the gas uptake is closed by means of the refractory wall, or partition 15. At the time the furnace is reversed, changing the introduction of the gas from the checker chamber 1 to the checker chamber 1^a, the partition described, but not shown, for blocking the gas port to permit the placing of the refractory wall or partition 15 is removed and the partition 19 inserted and the oil burner 18 placed in position. This done the firing of the furnace is accomplished with the use of oil in place of gas on this end of the furnace. Now during the interval of time when the first oil burner is used the gas port at the opposite end of the furnace is blocked off in the manner previously described and the gas uptake covered with a refractory wall to permit the introduction of the oil burner at that end of the furnace the products of combustion passing out through the air port, as previously described. During this work parts of the bulk-heads of the slag pockets are removed and the flues 14 and 14^a are connected thereto through the communicating necks 23. We now have the furnace completely changed from gas fired to oil fired and without any appreciable interruption to the operation of the furnace and the production of steel.

One of the plans previously devised for converting a gas fired furnace to an oil fired furnace which has come to my attention is to cut an opening through the partition walls 24 separating the gas and slag pockets 2 and 5 and 2^a and 5^a and block off the upper end of the gas uptakes by a refractory partition, such as I have shown at 15. The very serious objection to this manner of ac-

complishing this purpose is that the work of removing a part of the partition walls 24 is done on the interior of the furnace, whereas my work is all done exteriorly of the furnace. To remove a section of the partition walls 24 it goes without saying that the furnace must be completely shut down and permitted to cool several days before workmen can enter the slag pockets, which to say the least is a very expensive operation, particularly by reason of the loss of production. Then again if it is desired to reconvert the furnace from an oil fired to a gas fired approximately the same amount of time must be consumed, and the furnace shut down to permit the openings in the partition walls 24 to be re-blocked, and experience has shown that it is extremely difficult to make the partition walls gas tight, resulting in the burning of the gas and air in the slag pockets and destroying the refractory walls of slag pockets, as well as the uptakes. The cooling down of the furnace adds a further costly delay. Another form of converting from gas fired to oil fired which has come to my attention is to provide water-cooled oil burners which are inserted into the gas ports without blocking the gas uptakes. The serious objection to this method resides in the fact that the waste gases or products of combustion pass through the air ports alone as in my case, and it is found that the water-cooling reduces the temperature of the oil, thereby reducing the heat and seriously impairing the efficiency of the furnace as an oil burning furnace. Instead of using a water-cooled burner it has been attempted to burn oil through an ordinary type of oil burner, but this is objectionable for the reason that the intense heat produced by the waste gases or products of combustion makes it necessary to remove the burners at opposite ends of the furnace during each reversal of the furnace. This method is so inadequate that its use has been very limited if not entirely done away with.

While I have preferred to disclose the invention in connection with the use of fuel oil, it is apparent that I may use other concentrated fuels without departing from the spirit and scope of the invention.

What I claim is:—

1. A method of converting a gas fired regenerative furnace to a furnace suitable for burning more concentrated fuels, which consists in connecting the air and gas systems of the furnace exteriorly of the furnace, closing the usual gas ports, and introducing concentrated fuel supplying means into the furnace.

2. A method of converting a gas fired regenerative furnace to an oil fired furnace, which consists in connecting the gas and air slag pockets of the furnace exte-

- riorly of the furnace, closing the usual gas uptakes and gas ports, and introducing liquid fuel supplying means into the furnace through the gas ports.
5. 3. A method of converting a gas fired regenerative furnace to an oil fired furnace, which consists in connecting the gas and air slag pockets through their bulkheads, closing the usual gas uptakes and gas ports to eliminate the egress of the products of combustion and the ingress of the supplied gas, respectively, and introducing liquid fuel supplying means into the furnace.
10. 4. A method of converting a gas fired regenerative furnace to an oil fired furnace, which consists in removing portions of the bulkheads of the gas and air slag pockets and establishing communication between said gas and air slag pockets through the resulting openings, closing the usual gas uptakes and gas ports, and introducing liquid fuel supplying means into the furnace through the gas ports.
15. 5. In a regenerative furnace, in combination with the gas and air slag pockets, gas uptakes and gas ports, a flue providing means of communication between said slag pockets exteriorly of the furnace, means for closing the gas uptakes and gas ports against egress and ingress respectively, and oil burners arranged in said gas ports and communicating with the interior of the furnace and also connected to a source of supply.
20. 6. In a regenerative furnace, in combination with the gas and air slag pockets, gas uptakes and gas ports, a flue providing means of communication between said slag pockets exteriorly of the furnace, means closing the upper ends of the gas uptakes, a partition closing the inner end of each gas port and provided with an opening therein, and an oil burner in each gas port, said burners having their discharge ends protruding through the openings in said ports and connected at their opposite ends with a source of oil supply.
25. 7. In a regenerative furnace, in combination with the gas and air supply systems, and gas uptakes and gas ports thereof, a flue for each gas and air supply system located externally thereof, and communicating means between said flues and gas and air supply systems respectively, means for closing the gas uptakes and gas ports against egress and ingress respectively, and oil burners arranged in said gas ports and communicating with the interior of the furnace at their inner ends and connected with an oil supply at their outer ends.
30. 8. In a regenerative furnace, in combination with the gas and air supply systems and gas ports thereof, means connecting said gas and air supply systems exteriorly of the furnace, means for closing communication between said gas and air supply systems and said gas ports, means for closing the gas ports against ingress, and concentrated fuel burners arranged in said gas ports and communicating with the interior of the furnace and also connected to a source of supply.
35. 60. 65. 70. 75.

CHESTER A. KELLOGG.
